ABRADING TOOL

John F. Eisele, Pinekney, Mich.

Application March 12, 1947, Serial No. 734,138

10 Claims. (Cl. 51—187)

1

This invention relates to abrading tools and more particularly to holders for sheets of abrasive material.

The principal object of the present invention is to provide a tool of the above character, means for minimizing the clogging of sheets of abrasive material when the tool is in use.

A further object of the invention is to provide such a tool which can be adjusted to conform to curved surfaces on which the tool is used.

Another object is to provide such a tool which can be easily and economically manufactured.

For a thorough understanding of the invention, reference is made to the following description and accompanying drawings, wherein:

Figure 1 is a side elevational view of a sanding tool embodying the present invention;

Figure 2 is a plan view of the base of the tool, the grip member having been removed from the tool;

Figure 3 is a cross-sectional view taken on substantially the line 3—3 of Figure 1;

Figure 4 is a side elevational view similar to Figure 1 showing the base of the tool adjusted to fit a concave surface;

Figure 5 is a bottom plan view of the base; and

Figure 6 is a side elevational view of one of the clamping strips in the base.

The tool disclosed herein is designed to hold a sheet of abrasive material, such as sandpaper, emery paper, or the like, while the tool is reciprocated by hand upon the surface being worked upon. The tool is preferably connected by a flexible hose to a source of compressed air, and the tool is so designed that when thus connected, a stream of compressed air is continuously forced out between the base of the tool and the sheet of abrasive, thereby vibrating the latter and shaking small particles from the abrasive sheet, minimizing the clogging thereof. The base of the tool is flexible, so that it can be adjusted to fit variously curved surfaces.

In general, the tool comprises a flexible base 10 on which the abrasive sheet is supported, a grip 11 by which the tool may be held in the hand and by means of which the sheet of abrasive is clamped to the base, mechanism 12 for adjusting the curvature of the base, and means for introducing a stream of air between the base and the abrasive sheet.

The base 10 is formed from a plurality of relatively thin plates of metal 13 and 14, and a pad formed of a sheet of felt 15 and a sheet of rubber 16. There are two plates of metal 13, both identical. They are generally rectangular and each

2

is provided at one end with an upstanding flange 17. These two flanges are located in parallel relation and clamped against opposite faces of a metal spacer 18 which will be more fully described presently. The edges of the plate 13 remote from the flanges 17 are provided with flanges 19 of arcuate cross-section. See Figures 1 and 4.

The plates 14, of which there are two, are of approximately the same width as plates 13, but 10 are shorter. They are placed on top of the plates 13. An edge of each plate 14 is provided with an upstanding flange 20. The flanges 20 are positioned against the flanges 17, as seen in Figures 1 and 4.

15 The spacer 18 is a rectangular plate of metal having a hole 21 therethrough, and a slot 22 communicating with the hole and extending downwardly to the lower edge of the spacer.

The flanges 17 and 20 are clamped against the 20 spacer 18 by two metal strips 23, which are fastened in place by two machine screws 24. The strips 23 and flanges 17 and 18 all have holes therethrough registering with the hole 21 in the spacer 18. Each strip 23 is also provided with a 25 pair of laterally spaced tongues 25 struck from the metal thereof and bent outwardly and downwardly. See Figures 1, 4 and 6. A pair of parallel slots 32 extend downwardly from the top edge of each strip 23. See Figure 6.

30 The felt pad 15 is cemented to the under sides of plates 13 and curves upwardly over the flanges 19. A plurality of pieces of cord or flexible wire 26 are cemented to the bottom surface of the felt, as shown in Figure 5. The cords 26 are arranged 35 so that they radiate outwardly from the center of the felt sheet. The rubber sheet 16 is cemented to the cords 26 and the felt 15. Since the rubber sheet 16 is thin and soft it conforms to the irregular contour of the felt and cords and produces a plurality of downwardly opening shallow channels or grooves radiating from the center of the pad. A hole 27 is cut through the rubber and felt sheets to register with the slot 22 in the 40 spacer 18.

45 The grip 11 is a piece of relatively heavy, yet somewhat flexible metal, bent into U-shape. See Figure 1. The extremities of the grip are flanged laterally outwardly at 28. The bight of the grip is covered with a pad 29 of soft material. In the 50 center of the bight of the grip is a downwardly opening depression 30. See Figure 3.

The grip is employed as a handle to be grasped by the operator of the tool. It is also used to clamp a sheet of abrasive material 31 onto the base. The sheet of abrasive is cut sufficiently long

to cover the under side of the base and curve over the ends of the base into the channels formed by the curved flanges 19. The legs of the grip 11 are then sprung into the channels, with the flanges 23 engaging the abrasive and clamping the same against the insides of the flanges 16.

The mechanism 12 for adjusting the curvature of the base comprises a pair of parallel arms 33. The arms 33 are attached to a pair of thin flexible metal plates 34 of the configuration shown in Figure 2. The arms are pivotally connected to upturned ears 35 on opposite sides of the plates 34. The central portions of the arms are connected together by a bolt 36 and a spacing sleeve 37. Rigidly attached to the spacing sleeve 37 and extending radially thereof is a screw 38.

A relatively deep rectangular notch 39 is cut in each arm midway between its ends. The notches receive the flanges 17 and 20 and the spacer 18. The edges of the notches 39 fit into and slide vertically in the slots 22 in the clamping strips 23.

Two coil springs 40 having eyes 41 in the ends thereof are hooked onto the lugs 25 on the strips 23 and extend over the spacing sleeve 37. The springs are hooked onto the lugs 25 while under tension, thus holding the plates 34 against the top of the base, through the medium of the arms 33, the bolt 36 and the spacing sleeve 37.

An adjusting nut 42 is threaded onto the screw 38. The adjusting nut has an elongated sleeve 43, internally threaded at its lower end, screwed thereon. The upper end of the sleeve 43 is rounded to fit into the depression 36. Preferably a large knurled knob 44 is fixedly connected to the sleeve 43. The knob 44 has an annular flange 44a held between the nut 42 and the sleeve 43. The free end of the screw 38 is enlarged slightly after the nut 42 is threaded thereon to prevent removal of the latter.

A tubular coupling 45 having a port 46 in the side thereof is inserted into the hole 21 through the parts 17, 18, 20 and 23, and securely fastened therein. The port 46 is arranged to register with the slot 22 in the part 18. One end of the tubular coupling is closed by a suitable plug. To the other ends of the coupling is attached an air hose 47 which leads to any suitable source of compressed air (not shown). A suitable valve (not shown) for regulating the flow of air through the hose is provided somewhere in the air line.

In using the present invention, a sheet of abrasive material is clamped to the base as described above, and the valve in the air line opened. The tool is then applied to the surface to be sanded and manually reciprocated thereon, as in the case of the well known crude sandpaper block. A stream of air under pressure flows through the hose 47 and coupling 45, cut through the port 46, slot 22 and hole 21. The air cannot pass through the sheet of abrasive material. Therefore, it fans outwardly between the rubber sheet 16 and the abrasive through the shallow grooves between the ridges in the rubber sheet formed by the cords 25. In so doing it sets up a rapid vibration, or fluttering, of little magnitude in the abrasive sheet, thereby dislodging particles of dust abraded from the work surface, which ordinarily tend to fill the spaces between the abrasive particles on the sheet of abrasive material.

If the work surface is concave, the base can be flexed to conform thereto by turning the knob 44 so as to separate the base and grip. See Figure 4. It will be noted that force applied to the base is not applied to the center of the base, but is

transmitted through the arms 33 to the plates 34 between the center and the ends of the base. The force is distributed quite uniformly through the flexible plates 34 and thereby produces a smooth, uniform curve in the base. The arms 33 can slide up and down relative to the central rib formed of the parts 17, 18, 20 and 23, upward movement of the arms being resisted by the springs 40.

If the work surface is convex, the knob 44 is retracted sufficiently to release the sleeve 43 from the depression 36, and the knob 44, sleeve 43 and screw 38 are swung to one side, as shown in broken lines in Figure 1. Since the base is flexible it can then follow a convex surface merely by applying downward pressure on the grip 11.

From the foregoing it will be seen that the present invention provides an abrading tool which can be quickly adjusted to fit a plane or various curved surfaces. It prolongs the life of the sheets of abrasive material by minimizing clogging thereof. It can be simply and economically manufactured.

The scope of the invention is indicated in the appended claims.

25 I claim:

1. A device of the character described comprising a relatively thin, flexible sheet metal base having a central transversely extending upstanding rib, said rib having an air duct therein extending through the lower surface of said base centrally thereof, and means attached to said rib and associated with said air duct for forcing a current of air through said duct out beneath said base.

33 2. A device of the character described in claim 1 wherein the lower surface of the base is provided with downwardly opening grooves radiating toward the edges of said base from the lower end of said air duct.

39 3. A device of the character described comprising a relatively thin flexible base member, an arched relatively rigid grip member attached to said base member in spaced zones adjacent two opposite edges of said base member and spaced from said base member intermediate said zones, a relatively rigid arm extending between said zones and engaging said base member at spaced points spaced from said zones, spring means connecting said arms to said base intermediate the ends of said arm and biasing said arm toward said base member, and an extensible and contractible strut connected to said arm intermediate the ends of the latter and engaging said arched grip member centrally thereof.

55 4. A device of the character described in claim 3 wherein said strut is pivotally connected to said arm and is disengageable from said arched grip member when said strut is contracted a predetermined distance.

65 5. A device of the character described comprising a relatively thin flexible base member, a relatively rigid arched grip member attached to said base member in spaced zones adjacent two opposite edges of said base member and spaced from said base member intermediate said zones, a pair of laterally spaced apart relatively rigid arms extending between said zones and engaging said base member at spaced points spaced from said zones, and an extensible strut connected to said arms intermediate the ends of the latter and engaging said arched grip member centrally thereof.

70 6. A device of the character described in claim 5 wherein said strut is pivotally connected to said arms and is disengageable from said arched grip

member when said strut is contracted a predetermined distance.

7. A device of the character described in claim 5 wherein said strut comprises two parts connected together and movable axially of each other.

8. A device of the character described in claim 5 wherein said arms are connected to said base member by spring means attached to said arms and said base member intermediate the ends thereof, said spring means normally biasing said arms toward said base.

9. A device of the character described comprising a relatively thin flexible base member, an arched relatively rigid grip member attached to said base member in spaced zones adjacent two opposite edges of said base member and spaced from said base member intermediate said zones, a relatively rigid arm extending between said zones and engaging said base member at spaced apart points spaced from said zones, and a strut connected to said arm intermediate the ends of the latter and engaging said arched grip member centrally thereof, said strut being extensible and contractible whereby to vary the spacing of the central portions of the base member and grip member and thereby flex said base member.

10. A device of the character described in claim

9 wherein said strut is pivotally connected to said arm and is disengageable from said arched grip member when said strut is contracted a predetermined distance.

Certificate of Correction

Patent No. 2,464,385.

March 15, 1949.

JOHN F. EISELE

It is hereby certified that errors appear in the printed specification of the above numbered patent requiring correction as follows:

Column 1, line 5, after the word "provide" insert *in*; column 3, line 47, for "ends" read *end*;

and that the said Letters Patent should be read with these corrections therein that the same may conform to the record of the case in the Patent Office.

Signed and sealed this 23rd day of August, A. D. 1949.
